UNITED STATES PATENT OFFICE.

ISAAC E. PALMER, OF MIDDLETOWN, CONNECTICUT.

DESIGN FOR A HAMMOCK.

SPECIFICATION forming part of Design No. 25,625, dated June 9, 1896.

Application filed April 28, 1896. Serial No. 589,463. Term of patent 14 years.

To all whom it may concern:

Be it known that I, ISAAC E. PALMER, of Middletown, in the county of Middlesex and State of Connecticut, have invented and produced a new and original Design for Hammocks, of which the following is a specification, reference being had to the accompanying drawing, forming a part thereof.

The leading feature of my design consists in a hammock-body having the shape, when spread out in a plane, of a longitudinal section of a frustum of a cone.

In the accompanying drawing the hammock-body is denoted by A, its wider end by a, and its narrower end by a'. 15

What I claim is—

The design for a hammock-body, substantially as herein shown.

ISAAC E. PALMER.
